CLINKER CRUSHER FOR STOKERS

Frederick J. Hoffman, Allentown, Pa.

Application April 16, 1940, Serial No. 329,977

3 Claims. (Cl. 110—45)

The present invention relates to new and useful improvements in coal stokers burning anthracite coal and has for its primary object to provide a clinker crusher adapted for periodical movement into and out of position with respect to the bed of coals contained in the firepot and embodying means for removing and crushing the clinkers which form at the edge of the bed of coals, and also to pack the bed so as to eliminate and partially close airholes in the surface of the bed, thereby preventing cold air from the forced draft fan of the stoker from chilling the boiler.

A further object of the present invention is to provide a clinker crusher of this character constructed in the form of a concaved plate adapted to substantially conform to the shape of the bed of fire contained in the firepot, and having perforations in said plate to prevent smothering of the fire when the crusher is moved into position with respect to the fire.

A still further object is to provide an apparatus of this character of simple and practical construction, which is efficient and reliable in performance, relatively inexpensive to manufacture and install in operation and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a side elevational view.

Figure 2 is a front elevational view.

Figure 3 is a vertical sectional view through the plate forming the clinker crusher, and

Figure 4 is a top plan view thereof.

Referring now to the drawings in detail, the firepot of a furnace is designated by the dotted lines at 5, and a fragmentary portion of the walls of the furnace is shown at 6. Journalled in the walls of the furnace is a rock shaft 7 from an intermediate portion of which projects an angular arm 8, the arm preferably being constructed of sections including an outer section 9 connected to the inner section 10 by means of a sleeve 11 in the opposite ends of which the sections of the arm are inserted and adjustably secured in position by set screws 12.

To the outer end of the section 9 is secured the clinker crushing plate 13 which is in disk form and concaved at its under surface and of

a diameter substantially equal to the diameter of the firepot 5.

The plate 13 is formed with a plurality of slotted openings 14 as well as a plurality of perforations 15.

The rock shaft 7, at its end portions, is provided with a pair of angular extensions 16 projecting laterally from the shaft and on the outer ends thereof are adjustably secured weights 17. The extensions 16 and weights 17 are positioned outwardly of the walls of the furnace 6 and also disposed on the shaft, outwardly of the furnace, is an angular extension 18 extending in a direction opposite from the extensions 16 and having an upturned extremity 19 provided with a head 20 and with which is engaged the free end of a lever 21 adapted for actuation by a suitable intermittent mechanism (not shown) for periodically exerting a downward movement on the head 20 whereby to rock the shaft 7 in a direction for lowering the plate 13 into engagement with the firepot 5.

The edge of the plate 13 is adapted to engage clinkers formed on the edge of the firepot and thus to break and remove the clinkers therefrom, the concaved under surface of the plate 13 conforming substantially with the raised contour of the bed of fire contained in the firepot whereby to pack the fire and to close any air holes that might be formed therein through the formation of clinkers in the fire. The plate thus serves to shape the bed of fire and keep the same free from clinkers.

The weights 17 serve the purpose of raising the plate upon release by the operating lever 21.

It is believed the details of construction, advantages and manner of operation of the device will be readily understood from the foregoing without further detailed explanation.

Having thus described the invention, what I claim is:

1. A clinker crusher for firepots comprising a disk-like perforated plate member having a concaved under surface and means for moving the plate into covering position upon the pot for compressing the fire contained therein, certain of said perforations being formed in the side walls of the concavity of the plate to prevent clogging of the perforations by cinders when compressed by the plate, said perforations providing a draft for the fire when the plate is in covering position.

2. A clinker crusher for firepots comprising a disk-like plate member having a concaved under surface, a plurality of arcuate slotted openings in

the side walls of the concavity of the plate, and means for moving the plate into covering position upon the pot for compressing the fire contained therein, said slotted openings providing ventilation for the fire to prevent smothering thereof when the plate is in covering position.

3. A clinker crusher for firepots comprising a rock shaft, adapted for periodical rocking actuation, a sectional arm extending laterally from the shaft, means adjustably connecting the sections of the arm and a disk-like plate member

carried by the arm and having a concaved under surface adapted for movement by the shaft into covering position upon the pot for compressing the fire contained therein, said plate member having arcuate slots in its side wall out of the direct path of cinders when compressed by the plate to prevent clogging of the slots and thus provide ventilation for the fire when the plate is in covering position.

10

FREDERICK J. HOFFMAN.
